UNITED STATES PATENT OFFICE.

THEODORE C. COMBES, OF PHILADELPHIA, PENNSYLVANIA.

DESIGN FOR A SPOON.

SPECIFICATION forming part of Design No. 21,900, dated October 18, 1892.

Application filed June 24, 1892. Serial No. 437,915. Term of patent 7 years.

To all whom it may concern:

Be it known that I, THEODORE C. COMBES, a citizen of the United States, residing in the city and county of Philadelphia, State of Pennsylvania, have invented and produced a new and original Design for a Spoon, of which the following is a specification, reference being had to the accompanying drawings, forming part thereof.

10 The leading feature of my design for a spoon is, first, the body of the handle thereof, of the form of a student with cap and gown and a diploma in his hand; next, of the neck of the handle, of the form of a pile of books supporting a student and supported on an owl next to the bowl; finally, of a bowl of the form of a foot-ball, having thereon a lamp of knowledge and smoke issuing therefrom.

Figure 1 represents a view of the obverse 20 side of a spoon embodying my design. Fig. 2 represents a view of the reverse side thereof.

In the drawings, A designates the handle of a spoon, the same being of the form of a stu-

dent B, with cap C, gown D, and diploma E, the arms of the student being folded. 25

F designates the neck, the same being of the form of a pile of books G and an owl H, the student standing on the books and the owl resting on the bowl.

J designates the bowl, the back of the same 30 being of the form of a foot-ball K and having on the face the lamp of knowledge L, with smoke M issuing therefrom.

N designates a diamond-shaped figure as part of the neck and part of the bowl. 35

What I claim is—

1. In the design for a spoon, the obverse, as shown and described.

2. In the design for a spoon, the reverse, as shown and described. 40

3. The design for a spoon, substantially as described and shown.

THEODORE C. COMBES.
